BEARING PILE CONSTRUCTION

Gerald G. Greulich, Mount Lebanon, Pa.

Application November 23, 1938, Serial No. 242,084

2 Claims. (Cl. 61—53)

This invention relates to load-bearing pile constructions and particularly to the formation of a tapered enlargement thereon.

An object of the present invention is the provision of enlargements to the normal bearing pile section only in that portion of the pile which is in firm load-carrying soil.

A further object of the present invention is to provide lagging members upon the face of the flanges with the lagging members tapering so that the pile will develop high load capacities in clay or cohering soil.

Other objects and advantages will become apparent as the description proceeds, and reference

is had to the accompanying drawing in which:

Figure 1 is an elevation showing the pile provided with tapered timber lagging members fastened to the faces of the flanges of a conventional type H or I-shaped beam;

Figure 2 is an elevation taken at right angles to Figure 1, and showing the cap members for the top and bottom of the lagging members;

Figure 3 is a section on the line III—III of Figure 1;

Figure 4 is a section on the line IV—IV of Figure 1; and,

Figure 5 is a section on the line V—V of Figure 1.

In the drawing, the numeral 2 represents the main body portion of the bearing pile and comprises a conventional type H or I-shaped member extending down through the water and mud into the stratum of firm soil.

On that portion of the main body 2, which penetrates the firm soil stratum, there is provided a tapered enlargement 3. This enlargement, as shown in the figures, comprises wooden lagging members 4 secured to the flanges 5 of the H or I-shaped member by bolts or other securing devices 6. The lagging members, while shown as being formed of timber, may be, if desired, suitably formed metallic sections, precast concrete sections, or other suitable material, and, in each instance, the lagging members are tapered and gradually become smaller downward from the top of the enlarged portion.

These lagging members are provided with a straight face which abuts the outer faces of the flanges of the H or I-shaped member, while the opposite faces gradually taper downwardly from the upper edge toward the lower end thereof.

Secured to the top of the lagging members, by bolts or other securing devices 7, are metallic angle members 8. These metallic angle members are provided with notched portions 9 to

receive the flanges 5 of the H or I-beam to which they are rigidly secured in any conventional manner, such as by welding or the like.

At the lower end of the tapered enlargement, metallic angle members 20 are welded to the flanges of the H or I-beam in order to provide a support for the reduced end portion of the lagging members and protect said ends during the driving operation as well as to form a rugged offset capable of forcing its way through the soil under driving operations.

Under the present construction, there is provided a bearing pile construction having a tapered enlargement which increases in width or size toward its upper end and which is of materially greater cross-sectional area at the upper end than at the lower end when applied to the H or I-beam. This produces a bearing pile having greater load-carrying values in a relatively short length of point section so that the material in the pile above the point section can be utilized to better advantage.

While I have shown and described an embodiment of the present invention, it is to be understood that I do not wish to be limited exactly thereto, since various modifications may be made without departing from the scope of the invention, as defined by the following claims.

I claim:

1. In a steel bearing pile having an H or I-shaped cross section, lagging members secured to the outer faces of each flange of said bearing pile over that portion of the pile which is in firm load carrying soil, the outer faces of said lagging members tapering gradually downwardly from the upper edge toward the bottom edge to form in combination with the pile an area on said pile having a tapered enlargement and means for securing said lagging members to said bearing pile.

2. In a steel bearing pile having an H or I-shaped cross section, lagging members secured to the outer faces of each flange of said bearing pile, said lagging members each having a straight surface abutting the straight faces of said flanges and an oppositely disposed downwardly tapered surface forming in combination with the bearing pile a tapered enlargement over that portion of the bearing pile which is in firm load carrying soil, plates secured to said bearing pile for protecting the ends of said lagging members and means for securing said lagging members to said bearing pile.
